(57) **CLAIM**

The ornamental design for a graphical user interface for a display screen, as shown and described.

DESCRIPTION

FIG. 1 is a front view of a graphical user interface for a display screen showing our new design.

The broken line showing of a display screen, the text, the icons, the rectangular-shaped region is for illustrative purposes only and forms no part of the claimed design.

1 Claim, 1 Drawing Sheet

FIG. 1
